UNITED STATES PATENT OFFICE.

FREDRICK LANCASTER, OF NEW YORK, N. Y., ASSIGNOR TO JORDAN L. MOTT, OF SAME PLACE.

DESIGN FOR BOILER-STAND.

Specification forming part of Design No. 7,444, dated May 19, 1874; application filed May 1, 1874.
 [Term of Patent 7 years.]

To all whom it may concern:

Be it known that I, FREDRICK LANCASTER, of the city, county, and State of New York, have invented a new and original Design for a Boiler-Stand, of which the following is a specification:

The nature of my design for a boiler-stand is fully represented in the accompanying print of a wood engraving, to which reference is made.

The design consists of the ornamental configuration of the branches B. It also consists of the ornamental top figure C of the standard. It also consists of the ornamental flutes D and bands E of the standards; and it also consists of the ornamental figures *d e*, together with the fluted and plain rings of the base.

I claim as my invention—

1. The ornamental figures B for the branches

or arms in a design for a boiler-stand, as set forth.

2. The ornamental figure C for a design for the top of the standard of a boiler-stand, as shown and set forth.

3. The flutes D and bands E as a design for the standard of a boiler-stand, as set forth.

4. The design for the base of a boiler-stand, consisting of the figures *d e* and the fluted and plain bands, as set forth.

5. The design for a boiler-stand, consisting of the ornamental rim *a b c*, arm-figures B, standard top figure C, side flutes D, and band E, and the base-figures *d e*, and bands, all as set forth.

FREDRICK LANCASTER.
